United States Patent Office

Des. 208,627
Patented Sept. 19, 1967

208,627

HAND VACUUM CLEANER

Lawrence W. Bonzer, 4250 Long Beach Blvd.,
Long Beach, Calif. 90807

Filed Nov. 14, 1966, Ser. No. 4,647

Term of patent 14 years

(Cl. D9—2)

FIG.1

FIG.2

FIG.6

FIG.3

FIG.7

FIG.4

FIGURE 1 is a perspective view of a hand vacuum cleaner showing my new design;

FIGURE 2 is a top plan view of said vacuum cleaner;

FIGURE 3 is a side elevational view thereof;

FIGURE 4 is a bottom view of said vacuum cleaner;

FIGURE 5 is a side elevational view showing the side of the vacuum cleaner opposite that side disclosed in FIGURE 3;

FIGURE 6 is a rear elevational view of said vacuum cleaner; and

FIGURE 7 is a front elevational view thereof.

The electric cord is shown broken away in the views of drawing for convenience of illustration.

I claim:

The ornamental design for a hand vacuum cleaner, substantially as shown and described.
